(57) **CLAIM**

The ornamental design for a feeding bottle for a mammal, as shown and described.

DESCRIPTION

FIG. 1 is a front perspective, exploded view of the first embodiment of a feeding bottle for a mammal;

FIG. 2 is a front perspective view thereof;

FIG. 3 is a bottom perspective view thereof;

FIG. 4 is a front view, the rear view being a mirror image thereof;

FIG. 5 is a right view, the left view being a mirror image thereof;

FIG. 6 is a top view thereof;

FIG. 7 is a bottom view thereof;

FIG. 8 is a front perspective view of a second embodiment of a feeding bottle for a mammal;

FIG. 9 is a front perspective view thereof;

FIG. 10 is a bottom perspective view thereof;

FIG. 11 is a front view, the rear view being a mirror image thereof;

FIG. 12 is a right view, the left view being a mirror image thereof;

FIG. 13 is a top view thereof;

FIG. 14 is a bottom thereof;

FIG. 15 is a front perspective view of a third embodiment of a feeding bottle for a mammal;

FIG. 16 is a front perspective view thereof;

FIG. 17 is a bottom perspective view thereof;

FIG. 18 is a front view thereof;

FIG. 19 is a right view thereof;

FIG. 20 is a top view thereof; and,

FIG. 21 is a bottom view thereof.

The broken lines illustrate portions of the feeding bottle for a mammal that form no part of the claimed design.

1 Claim, 18 Drawing Sheets
